UNITED STATES PATENT OFFICE

155,861

DESIGN FOR A COMBINED SUPPORTING STAND AND BAR ACCESSORIES

William D. Adams, Tampa, Fla.

Application June 28, 1948, Serial No. 147,249

Term of patent 7 years

(Cl. D44—29)

To all whom it may concern:

Be it known that I, William D. Adams, a citizen of the United States, residing at Tampa, in the county of Hillsborough and State of Florida, have invented a new, original, and ornamental Design for a Combined Supporting Stand and Bar Accessories, of which the following is a specification, reference being had to the accompanying drawing, forming a part thereof.

The essential features of my design reside in those portions shown in full lines.

I claim:

The ornamental design for a combined supporting stand and bar accessories, as shown and described.

WILLIAM D. ADAMS.
